S. Thomas

ATTORNEY

UNITED STATES PATENT OFFICE.

ALEXANDER OZEROWICZ, OF DETROIT, MICHIGAN.

MECHANIC'S TOOL.

1,841,757.

Specification of Letters Patent.

Patented June 1, 1920.

Application filed February 6, 1919. Serial No. 275,396.

To all whom it may concern:

Be it known that I, ALEXANDER OZEROWICZ, citizen of Russia, residing at Detroit, county of Wayne, State of Michigan, have 5 invented a certain new and useful Improvement in Mechanics' Tools, and declare the following to be a full, clear, and exact description of the same, such as will enable others skilled in the art to which it pertains 10 to make and use the same, reference being had to the accompanying drawings, which form a part of this specification.

My invention relates to a mechanic's tool, and one of its objects is to combine in a single instrument a plural number of tools that are not a mere aggregation of unrelated elements but are adapted to coöperate with each other in the performance of the necessary successive operations required in the 20 production of certain manufactured articles:—the several elements being combined in a single unit that they may be ready for instant progressive use or service and whereby they may not be mislaid or lost.

25 Another object of the invention is to provide means whereby it may be rapidly and accurately adjusted for the performance of its several functions.

Another feature of the device is its adapt- 30 ability to be folded into a compact form convenient for carrying in the pocket.

The instrument comprises the following elements combined in a frame which coöperates in their adjustment and support:—a 35 pair of compasses or dividers, the legs of which telescope in a hinged portion of the frame having a link connection with a graduated nut, the latter being adapted to indicate the degree of adjustment given to the 40 legs:—“inside” and “outside” caliper legs also supported in the hinged portion of the frame,—the adjustment of which is also predetermined by the graduated nut:—a plumb “bob” pointer which also serves as the sup- 45 port on which the graduated nut is mounted and coöperates therewith:—a level which coöperates with the plumb, and also with the caliper and legs of the divider in determining certain measurements:—and a marking 50 gage comprising a rotatable marker mounted on one end of the divider legs:—the same clamping elements which serve to secure the legs of the divider serving to secure said legs when adjusted as a marking gage.

55 With the foregoing and other objects in

view, which will appear as the description proceeds, the invention resides in the combination and arrangement of parts and in the details of construction hereinafter described and claimed, it being understood 60 that changes may be made in the precise embodiment herein disclosed without departing from the spirit of the same.

In the accompanying drawings:—

Figure 1 is a side elevation of the device 65 with the divider legs extended.

Fig. 2 is a side elevation of the same, with a portion of the supporting frame in section, and showing in dotted lines one pair of the 70 caliper legs extended.

Fig. 3 is a cross-sectional view on line 3—3 of Fig. 1, the lower portion of the spiral groove being shown in dotted lines.

Fig. 4 is a sectional view on line 4—4 of Fig. 1, showing in dotted lines one portion 75 of the “base” frame extended when used in leveling or making other measurements.

Fig. 5 is a cross-sectional view of a detail of construction taken on line 5—5 of Fig. 2, showing the slidable clamping member 80 employed to secure the divider leg and marking gage.

Referring now to the letters of reference placed upon the drawings:—

A, denotes a portion of the frame, having 85 lateral extensions A¹, dovetailed thereto to supply when adjusted a relatively long base for the “level” B;—in turn pivoted by a pin 3 or other suitable pivot in an opening in the frame A, and having a pointer B¹, co- 90 operating with certain graduations B², in the wall of the frame surrounding the opening, that the angularity of the part tested may be determined. The level B which is of the ordinary construction, is provided at 95 the top with a pointer, and its lower portion constitutes a weight which maintains the pointer in a perpendicular position and enables the pointer to coöperate with the graduations B². A², A³ designate swinging 100 members of the frame A, pivoted at α , thereto. A³, are covers hinged to each side of the swinging members A², adapted to close and maintain in position when adjusted, the legs of the respective “inside” and “outside” 105 calipers C, C¹. The calipers are secured to the swinging members A² by an overlapping end portion of the frame A⁴, in addition to the hinged covers A³, which latter are provided with inwardly directed pins D, adapt- 110

ed to enter apertures D^1 , in the legs of the calipers to secure them in their adjusted positions upon the covers being closed over the legs of the calipers:—The covers are also 5 provided with a suitable detent or latch e , to secure them when closed.

10 E , indicates a plumb bob "pointer", consisting of a rod fitted with a detachable pointed end E^1 , which has a socket and tenon connection with the rod and which may be removed should occasion require in order to provide greater latitude in the use of the caliper legs when making certain measurements.

15 F , indicates a rotatable nut mounted upon the rod E , and the latter is provided with a spiral groove E^2 , to receive a ball G , partially lodged in a groove F^1 , formed in the nut F ;—the ball being held against displacement by a screw H , extending through the wall of the nut. I , designates an open slideable frame mounted on the rod E , adapted to receive the nut F , and travel with it along the rod. J, J , are links connecting the slideable frame I , with the respective swinging members A^2 , of the frame A , and upon rotating the nut F , the swinging legs with the respective divider or caliper legs carried thereby, may be given any predetermined 20 adjustment as determined by the graduations F^2 , upon the nut in conjunction with the pointer I^1 , on the frame I . The spiral groove E^2 and the ball G provide a rapid and easy adjustment for the pivoted member 25 A and enable the nut to coöperate with a groove of a greater pitch and consequently there is provided more rapid adjustment than with an ordinary thread and nut.

30 K , denotes a set screw in frame I , adapted to bear upon the rod E , to secure the parts when adjusted.

35 L, L , indicates cam-shaped clamping devices having projecting trunnions L^1 , extending into longitudinal grooves L^2 , in the walls of the swinging members A^2 , of the frame, adapted to secure the divider legs or gage rods P , in their respective adjusted positions:—the clamping members being 40 adapted to slide in the grooves to accommodate themselves to the position of the legs.

45 M , designates a loop in the frame A , to receive a connecting cord (not shown) that the device may serve as a plumb, the rod E , and its pointed end E^1 serving as the "pointer."

50 N , is a rotatable disk on the end of the divider legs P , to provide a scratch gage;—the legs being adjusted through openings in the frame provided for their passage.

55 Having indicated the several parts by reference letters, the construction and operation of the device will be readily understood.

60 When folded the device may be readily carried in the pocket, and it may be used as

a plumb by attaching a cord to the ring or loop M :—or as a level by adjusting the lateral extensions A^1 of the frame. When a cord is attached to the loop M the device operates as a plumb bob and is arranged in an inverted position, the pointed end E^1 constituting the point of the plumb bob. The sections or members A^1 , which are mounted in a dovetailed guide 2 are adapted to slide inwardly and outwardly and when the sections or members A^1 are extended they coöperate with the pivoted level B and the graduations B^2 will indicate the variations of an inclined surface from a horizontal plane.

65 When it is desired to describe a predetermined arc with the dividers, or make certain measurements with the calipers, the swinging members of the frame carrying these parts may be adjusted to any desired degree within the capacity of the device by the adjustment of the graduated nut F . It will be noted that the covers A^3 , hinged to the swinging members of the frame, perform a double function, namely, to secure 70 the legs of the calipers against displacement when adjusted and to provide a smooth even surface that the device may be conveniently handled.

Having described my invention what 75 I claim is:—

1. A device of the character described, the combination of a frame having a pair of members pivoted thereto, a plurality of adjustable legs carried by the members, a rod 100 having a spiral groove extending from the frame between the members, a nut mounted upon the rod, a ball carried by the nut and projecting into the spiral groove in the rod, a slideable frame sleeved upon the rod and 105 embracing the nut, whereby it may travel therewith along the rod, and links connecting the slideable frame with the respective members of said first named frame.

2. In a device of the character described, the combination of a frame having a pair of members pivoted thereto, a plurality of adjustable legs carried by the members, means for respectively securing said legs when adjusted, a rod having a spiral groove 110 fixed to the frame and extending midway between the swinging members, a grooved nut mounted upon the rod, a ball lodged in a groove in the nut and extending into the spiral groove in the rod, a slideable frame 115 sleeved upon the rod and partially inclosing the nut, whereby it may travel with the nut upon adjusting the latter, and links connecting the slideable frame with the swinging members of the first named frame.

3. In a device of the character described, the combination of a frame, having a pair of pivoted members, adjustable legs slideable on the pivoted members, covers hinged to the pivoted members and arranged to em-130

brace and adjustably secure the said legs to the pivoted members, and means for adjusting the pivoted members.

4. A device of the class described including a frame provided with a pair of pivoted members, a plurality of adjustable legs carried by each of the pivoted members and located at opposite sides of the same, and covers hinged to the said members and embracing the said legs and provided with means for securing the legs in their adjustment, and means for adjusting the pivoted members.

5. In a device of the character described, the combination of a frame having a pair of members pivoted thereto of channel like form in cross-section and provided with grooves, adjustable legs lodged in said channels, and slid able cam-shaped clamping members having trunnions projecting into said grooves, whereby upon adjusting the

cam-shaped clamping members the adjustable legs may be secured to the members of the frame.

6. A device of the character described including a frame, having a pair of pivoted members of channel-like form in cross section, adjustable legs lodged in the channels, means for securing such legs in their adjustment, exteriorly arranged legs located at opposite sides of the pivoted members, and covers hinged to the pivoted members and embracing the exterior legs and provided with means for securing the same in their adjustment.

In testimony whereof, I sign this specification in the presence of two witnesses.

ALEXANDER OZEROWICZ.
